United States Patent

Des. 239,667
Patented Apr. 27, 1976

239,667

SWIM SUIT

Eleanor Bouchard, Miller Hill Road,
Dover, Mass. 02030

Filed Apr. 24, 1974, Ser. No. 463,466

Term of patent 14 years

Int. Cl. D2—02

U.S. Cl. D2—25

FIG. 1

FIG. 2

FIG. 3

FIG. 1 is a front perspective view of a swim suit showing my new design;

FIG. 2 is a rear perspective view; and

FIG. 3 is a top plan view showing the swim suit spread on a flat surface.

I claim:

The ornamental design for a swim suit, as shown and described.
